UNITED STATES PATENT OFFICE

2,471,673

WEIGHT-OPERATED AIR PUMP

Charles Coté, Windsor, Ontario, Canada

Application December 3, 1945, Serial No. 632,527

4 Claims. (Cl. 230—216)

1

The present invention pertains to a novel pump designed to compress air for use at gasoline stations, and other automobile service installations. The principal object of the invention is to dispense with the motor-driven compressor usually required for such purposes and to replace it by an air pump or compressor actuated by the weight of the vehicles entering the station.

This object is accomplished, generally, by a pumping unit or a plurality of them, embedded in the pavement and having an exposed, slightly elevated dome connected to a piston in a cylinder. A vehicle riding over the dome depresses it and performs the compression stroke of the pump. At the same time, a number of springs are compressed, and when the weight of the vehicle is removed from the dome, the springs elevate the dome and piston and perform the intake stroke.

More specifically, the device is reinforced by braces extending across the interior of the outer frame, and the dome carries depending guide sleeves slidable through the braces. The lower ends of the sleeves receive the upper ends of guide rods mounted in the base of the frame, and coil springs surround the respective rods beneath the guide sleeves. This is the spring construction that elevates the dome to perform the intake stroke of the piston. The invention further includes rollers or thrust bearings mounted externally in the frame and extending into the side walls thereof sufficiently to be engaged by the dome for guiding the latter in its vertical movement. These bearings are housed beneath outwardly extending flanges at the top of the frame. These flanges, when inserted flush in the pavement, determine the proper position of the unit with respect to the pavement.

The invention is fully disclosed by way of example in the following description and in the accompanying drawings in which:

Figure 1 is a side elevation of the device, partly in section;

Figure 2 is a plan section on the line 2—2 of Figure 1, and

Figure 3 is an end view, one of the end walls being partly broken away.

Reference to these views will now be made by use of like characters which are employed to designate corresponding parts throughout.

In Figure 1 is shown a frame or housing 1 adapted to be laid in a pavement and having at its upper edge a pair of outwardly extending flanges 2 that are set in the pavement at the surface or ground level thereof. In the angles formed by the flanges are provided webs 3 which

2

support horizontally journaled rollers or thrust bearings 4 extending into appropriate recesses in the adjacent sides of the member 1, as may be seen in Figure 1.

On the bottom of the member 1 is secured a vertical cylinder 6 fitted with a suitable cap 7. A piston 8 is slidably mounted in the cylinder and fitted with a piston rod 9 extending through the cap 7 where it is enclosed in a sealed bushing 10. In the upper open end of the frame 1 is slidably mounted a dome 11 having end lugs 12 which engage the rollers 3 and are guided vertically thereby. The lower surface of the dome 11 is attached to the upper end of the piston rod 9 by a suitable ball and socket designated by the numeral 13.

At the bottom of the cylinder 6 is formed an air intake port 14 connected by a nipple 15 to a check valve 16 which opens towards the intake port. An air line 17 leading from a suitable air cleaner extends to the intake side of the check valve 16.

Opposite the port 14 and also at the bottom of the cylinder 6 is formed a similar outlet port 18 connected by a nipple 19 to a check valve 20 which opens away from the nipple. From the outlet side of the check valve 20, an air line 21 extends to a suitable storage tank. It will be understood that the check valves 16 and 20 may be of the spring-pressed ball type or other suitable design.

A pair of channel braces 22 are secured lengthwise between the sides of the frame 1 and directly beneath the thrust bearings 3. Four guide sleeves 23 are fixed to and suspended from the dome 11 and received slidably in the ends of the respective braces 22. Vertical guide rods 24 are fixed on the bottom of the frame 1 and received respectively in the sleeves 23. Each rod 24 is surrounded by a compressed coil spring 25 having its lower end engaging a seat 26 at the bottom of the rod and its upper end bearing against a flange 27 at the lower end of the corresponding sleeve 23.

As previously indicated, the device is installed so that the flanges 2 are at the surface level of the pavement and the dome 11 consequently extends somewhat above the surface. The device is positioned to lie in the path of the wheels of a motor vehicle approaching a gasoline pump or other essential piece of service equipment. The weight of the vehicle depresses the dome 11 and with it the piston 8, compressing air in the cylinder below the piston and forcing it through the outlet port 18 and check valve 20 to the line 21 leading to the storage tank.

When the weight of the vehicle has been re-

moved from the dome 11, the latter is lifted by the expansion of the springs 25 which were compressed on the downstroke. The resultant upward movement of the piston 8 draws air through the intake line 17 and check valve 16 to the lower portion of the cylinder 6 below the piston 8, in readiness for the next compression stroke as previously described.

Several such devices may be distributed over the pavement of the service station, if desired, at least in sufficient number to maintain the necessary quantity of compressed air for inflating tires and other purposes. Thus, the cost of installing and maintaining a motor driven compressor is materially reduced by provision of one or more of the relatively inexpensive pumps herein described.

Although a specific embodiment of the invention has been illustrated and described, it will be understood that various alterations in the details of construction may be made without departing from the scope of the invention as indicated by the appended claims:

What I claim as my invention is:

1. A weight-operated pump comprising a frame adapted to be embedded in a pavement, a dome slidably mounted in said frame and normally extending beyond the top of said frame, braces mounted in said frame, guide sleeves carried by said dome and passing slidably through said braces, guide rods fixed to the bottom of said frame and having their free ends slidably received in said sleeves, whereby to provide bearing surfaces for said rods rigid with an in close proximity to said dome, a cylinder mounted in said frame beneath said dome, a piston in said cylinder, a piston rod extending from said piston and connected to said dome, and valve-controlled inlet and outlet means associated with said cylinder.

2. A weight-operated pump comprising a frame adapted to be embedded in a pavement, a dome slidably mounted in said frame and normally extending beyond the top of said frame, braces mounted in said frame, guide sleeves carried by said dome and passing slidably through said braces, guide rods fixed to the bottom of said frame and having their free ends slidably received in said sleeves, whereby to provide bearing surfaces for said rods rigid with and in close proximity to said dome, a cylinder mounted in said frame beneath said dome, a piston in said

cylinder, a piston rod extending from said piston and connected to said dome, spring means compressible on depression of said dome, and valve-controlled inlet and outlet means associated with said cylinder.

3. A weight-operated pump comprising a frame adapted to be embedded in a pavement, a dome slidably mounted in said frame and normally extending beyond the top of said frame, braces mounted in said frame, guide sleeves carried by said dome and passing slidably through said braces, guide rods mounted on the bottom of said frame and slidably received in said sleeves, whereby to provide bearing surfaces for said rods rigid with and in close proximity to said dome, coil springs surrounding said rods and bearing against said sleeves, a cylinder mounted in said frame beneath said dome, a piston in said cylinder, a piston rod extending from said piston and connected to said dome, and valve-controlled inlet and outlet means associated with said cylinder.

4. A weight-operated pump comprising a frame adapted to be embedded in a pavement, a dome slidably mounted in said frame and normally extending beyond the top of said frame, flanges extending outwardly from the top of said frame and adapted to lie flush with the surface of the pavement, rotary guide members carried outwardly of said frame beneath said flanges and engageable by said dome, a cylinder mounted in said frame beneath said dome, a piston in said cylinder, a piston rod extending from said piston and connected to said dome, and valve-controlled inlet and outlet means associated with said cylinder.

CHARLES COTÉ.
